UNITED STATES PATENT OFFICE.

EMIL P. SCHWARZ, OF ST. PAUL, MINNESOTA.

WRENCH.

1,399,890.

Specification of Letters Patent. Patented Dec. 13, 1921.

Application filed December 30, 1919. Serial No. 348,428.

To all whom it may concern:

Be it known that I, EMIL P. SCHWARZ, residing at St. Paul, in the county of Ramsey and State of Minnesota, have invented a new and useful Improvement in Wrenches, of which the following is a specification.

This invention relates to improvements in wrenches of that character in which a stationary jaw member is formed integral with a threaded handle bar, a movable jaw member is adjustably mounted and arranged to coöperate with the stationary jaw member for use in turning or holding different sizes of pipes, nuts and bolt heads, and a yoke frame carrying the movable jaw member is adjustably arranged to slide back and forth on the handle of the stationary jaw member and to be moved into and out of a screw adjusting connection therewith. More particularly this invention relates to a modification of the construction disclosed in my companion application filed August 29, 1919, bearing Ser. No. 320,650. In the present application the movable jaw member is pivotally mounted upon the yoke member and is guided and supported laterally in an improved manner, the yoke member being so constructed as to pivotally support the movable jaw member in a strong and efficient manner, thus producing a wrench which is particularly adapted for holding or turning pipes and whereby the jaws can be easily and quickly adjusted to any size of work.

In the accompanying drawings forming part of this specification, Figure 1 is a side elevation of my invention; Fig. 2 is a view similar to that illustrated in Fig. 1, except that a portion thereof is shown in central longitudinal section, and Fig. 3 is a cross sectional view taken on the line 3—3 of Fig. 1.

In the drawing A indicates the stationary jaw member having the integral rack handle bar B threaded at 10 on one edge and formed with a serrated work gripping surface 11. D indicates the movable jaw member which has a serrated work gripping surface 12 adapted to coöperate with the gripping surface 11. This movable jaw member has a rock bar or shank 13 extending over the stationary jaw member and resting upon the surface or bearing 14 of the stationary member which acts as a fulcrum 50 above the threaded edge of the shank B. This fulcrum member has a pair of lips or

flanges 15 between which the shank 13 is held laterally and by which a side support is formed for bracing the movable jaw member. The rearward end of the shank 13 is secured in a yoke member E by means of the pivot 16.

The yoke member E is formed with a longitudinal passage 17 through which the handle bar B passes. It is also formed with a forwardly projecting body 18 in which is a longitudinal aperture 19 which receives the outer end of the shank 13 and across which the pivot 16 is secured. The yoke member is free to slide on the shank B, its body portion being of sufficient length to form a strong and substantial connection on shank B. The main body portion of the yoke member has a transverse opening 20 above the teeth 10 on the handle bar in which opening is rotatably mounted the adjusting screw F which is accessible through the sides of the yoke member for turning by hand. Thus there is formed a bar 21 which reinforces the structural strength of the yoke member, the structure resembling a yoke spanning the screw closed at opposite side portions of the screw and reducing all tendency to bind the screw. The screw has a shaft 22 fixed on its axis the ends of which resemble trunnions which revolve freely in verticle guide passages 23 and 24 in the body of the yoke member, the opening 24 extending rearwardly so that the shaft can be inserted in the screw after the latter has been placed in the opening 20. Positioned above the trunnions on the screw are a pair of receptacles 25 and 26 which hold a pair of helical springs 27 and 28 pressing down upon the trunnions. These springs releasably hold the screw with its threads engaging the threads of the handle bar. The threads of the screw and handle bar are substantially square in cross section to prevent any tendency to disengage when the jaws are applied under pressure to turn the pipe, nut bolts or other work. The springs are removable from their receptacles by removing threaded cover pieces 29 in the outer ends of the receptacles. The outermost edge of the rearward end of the shank 13 is formed with an outermost clearance depression 30 which permits a limited tilting movement of the movable jaw member thus causing the jaws to bite firmly when the wrench is turned against the work.

The yoke shaped structure constituting

the main body of the screw holding member having closed outer and inner ends and formed with a forwardly projecting body having an aperture pivotally holding the 5 rearward end of the shank of the movable jaw member and the stationary jaw member formed with a fulcrum having outwardly projecting side guiding members between which the shank of the movable jaw member 10 is supported constitute a unique strong and effective structure adapted particularly for use in turning or holding pipes or other objects.

In accordance with the patent statutes I 15 have described the principles of operation of my invention together with the apparatus which I now consider to represent the best embodiment thereof, but I desire to have it understood that the construction shown is 20 only illustrative and that the invention can be carried out by other means and applied to uses other than those above set forth within the scope of the following claim.

Having described my invention, what I 25 claim as new and desire to protect by Letters Patent, is:—

A wrench, comprising, in combination, a stationary jaw member having a handle bar, thread engaging teeth on one edge of the 30 handle bar, a jaw extending from one end of the handle bar, side guides projecting from the jaw portion and a bearing between said side guides, a yoke sliding longitudinally on said handle bar having an aperture 35 in one end and a transverse passage across

said engaging teeth, said passage being closed at its outer end by an integral connecting portion and formed with a handle bar receiving longitudinal guide way at the inner end of said transverse passage, said 40 yoke member being also formed with outwardly extending longitudinal gudgeon guide passages, and with outwardly extending spring holding receptacles open at their outer ends to receive springs and connecting with said guide passages, a screw in said transverse passage having gudgeons in and movable outwardly in said guide passages, a spring in each of said receptacles bearing 45 downwardly against said gudgeons and releasably urging said screw with its teeth into engagement with the teeth of said handle bar, a movable jaw member having a rock bar pivotally secured at one extremity in said aperture, and a jaw on its free end adapted to coöperate with said stationary 50 jaw, said rock bar being fulcrumed freely on the bearing between said side guides, the inner surface of said aperture and the back of said rock bar being formed with a clearance space adapted to permit only limited 55 free outward tilting movement of the rock bar in the yoke and consequent limited opening movement of the movable jaw, and closures in the outer ends of said spring holding receptacles.

In testimony whereof, I have signed my name to this specification.

EMIL P. SCHWARZ.
